UNITED STATES PATENT OFFICE.

EDWARD B. MALLORY, OF CHICAGO, ILLINOIS, ASSIGNOR TO ECONOMY FUSE & MANUFACTURING COMPANY, OF NEW YORK, N. Y., A CORPORATION OF NEW YORK.

CARTRIDGE-FUSE.

1,092,153.

Specification of Letters Patent. Patented Apr. 7, 1914.

Application filed September 9, 1912, Serial No. 719,282. Renewed November 20, 1913. Serial No. 302,154.

To all whom it may concern:

Be it known that I, EDWARD B. MALLORY, a citizen of the United States, residing at Chicago, in the county of Cook and State of Illinois, have invented certain new and useful Improvements in Cartridge-Fuses, of which the following is a specification.

My invention relates to cartridge fuses, and refers particularly to that type of fuse known as the refillable fuse in which the fusible element may be replaced after it has been melted or burned out.

It is the object of my invention to provide a cartridge fuse in which the contact blades are quickly and easily alined with each other in the hollow insulating body of the cartridge.

It is a further object of my invention to construct the various parts so that they are cheap to manufacture, while at the same time the operation of the fuse as a whole is efficient, and the parts may be quickly adjusted in position when it is desired to replace the fusible element.

A further object is to provide parts of such nature that when a blow-out occurs the escaping gases will be directed toward the contact blades and not toward the clips adapted to receive the contact blades with consequent injury to such clips and liability to cause fire in the presence of inflammable material.

A further object of my invention consists in providing in the cartridge fuse of my invention a special form of fusible element which reduces the amount of gases generated in case of a blow-out when a great excess of current passes through the fuse, while the fusible element does not become unduly heated under normal working conditions.

These and other advantages of my invention will be more readily understood by reference to the accompanying drawings, which show a preferred embodiment of my invention, and in which—

Figure 1 is a longitudinal section through my improved cartridge fuse; Fig. 2 is a longitudinal section similar to Fig. 1, but taken at right angles thereto; Fig. 3 is a plan of one of the centering washers used in connection with my fuse; Fig. 4 is a sectional view taken on the line 4—4 of Fig. 3; Fig. 5 is a plan of the centering washer adapted to operate with the washer shown in Figs. 3

and 4; Fig. 6 is a sectional view taken on the line 6—6 of Fig. 5; Fig. 7 is a sectional view taken on the line 7—7 of Fig. 2; Fig. 8 is a plan of the fusible element used in my cartridge fuse; Fig. 9 is a side elevation of the fusible element shown in Fig. 8; and, Fig. 10 is a longitudinal section of a portion of the insulating body element.

The hollow insulating body element 20 is provided with the threaded ends 21 and with the alining notches 22. Each of the contact blades 23, as most clearly shown in Fig. 2, has a narrow end portion 24 and a centering aperture 25. Passing through the aperture 25 of each contact blade 23 is the tongue 26 of the washer 27, the tongue 26 being formed by cutting the slots 28 in said washer. To the inner surface of the washer 27 is riveted or otherwise suitably fastened the alining element 29, which is adapted to engage the notches 22 of the insulating body 20 when the tongue 26 of the washer 27 is slipped through the aperture 25 of the contact blade 23. After the washer 27 has been placed in position, the centering tongue 30 of the washer 31 is passed through the aperture 25 of the contact blade 23 from the opposite direction from that in which the tongue 26 of the washer 27 is passed through said aperture. In this way the opposite surfaces of the contact blade are held between the bases of the slots 28 of the washer 27 and the bases of the slots 32 of the washer 31. The cap 33 is applied to the threaded end of the insulating body 20, and serves to hold the centering washers 27 and 31 in position. It will be observed that a slight annular space 34 is formed between the inside of the cap 33 and the outer peripheries of the washers 27 and 31.

The fusible element 35 is provided with enlarged ends 36, each of which has an aperture 37. The central portion 38 of the fusible element 35 is of the proper size to melt at the predetermined rating of the fuse. It will be evident that since the main portions 38 of the fusible element are of less width than the enlarged ends 36, when a blow-out occurs, under severe conditions, the amount of gas generated will be reduced below that which would be generated if the portions 38 were of the same width as the ends 36, while in a normal blow-out, in which the amount of current is slightly in excess of the

fuse rating, only the restricted portion 38 will be affected. The ends 36 of the fusible element 35 are attached to the ends of the contact blades 23 by means of the bolts 39 having the nuts 40, the washers 41 being preferably employed between the ends 37 of the fusible element 36 and the head of the bolt 39 and the nut 40. On account of the enlarged ends of the fusible element 35 an excellent contact is obtained between the latter and the contact blades 23. The insulating body 20 may be filled with any suitable packing.

After the various parts have been placed in position as just described, it will be evident that in case of a blow-out the gases will first pass through the passages which are formed by the slots 28 in the washers 27. These gases next pass through the annular space 34 between the peripheries of the washers and the caps 33 and finally pass through the slots 32 of the washers 31, and are thus directed toward the contact blades 23 instead of being directed in a line parallel to the contact blades themselves. In this way the liability of fire is greatly reduced, since the inflammable gases do not pass to nearly as great a distance from the ends of the cartridge.

After a blow-out each of the caps 33 is removed and the pair of centering washers are next removed from one of the contact blades 23. The contact blades being removed from the insulating body 20, a new fusible element 35 is attached to said contact blades; the blade from which the washers have been removed is passed through the insulating body 20 into position, the cap for the opposite contact blade is applied, the cartridge is filled with packing, the centering washers are applied to the contact blade first mentioned, its cap 33 is screwed onto the end of the insulating body 20, and the cartridge fuse is again ready for use.

It will be apparent to those skilled in the art that many changes could be made in the detail construction of the various parts which I have described without departing from the spirit or scope of my invention.

What I claim is:

1. In a cartridge fuse, the combination of a hollow insulating body, a pair of contact blades having apertures therein, a fusible element, means for attaching said fusible element to said contact blades, removable means passing through the apertures of said contact blades for centering the latter in said insulating body, and means for holding said centering means in position, substantially as described.

2. In a cartridge fuse, the combination of a hollow insulating body, a pair of contact blades having apertures therein, a fusible element, means for attaching said fusible element to said contact blades, a centering

washer passing through an aperture of each of said contact blades, and means for holding said washers in position at the ends of said insulating body, substantially as described.

3. In a refillable cartridge fuse, the combination of a hollow insulating body, a pair of contact blades having apertures therein, a fusible element, means for attaching said fusible element to said contact blades, removable means passing through the apertures of said contact blades and engaging the ends of said insulating body for centering said blades in said insulating body, and means for holding said centering means in position, substantially as described.

4. In a refillable cartridge fuse, the combination of a hollow insulating body having alining notches in its ends, a pair of contact blades adapted to enter opposite ends of said insulating body, each of said blades having an aperture therethrough, and alining and centering means having removable engagement with said contact blades and passing through the apertures in the latter, said alining and centering means having portions engaging the alining notches in the ends of said insulating body, substantially as described.

5. In a refillable cartridge fuse, the combination of a hollow insulating body having alining notches in its ends, a pair of contact blades adapted to enter opposite ends of said insulating body, each of said blades having an aperture therethrough, alining and centering means having removable engagement with said contact blades and passing through the apertures in the latter, said alining and centering means having portions engaging the alining notches in the ends of said insulating body, and means for locking said alining and centering means in position, substantially as described.

6. In a refillable cartridge fuse, the combination of a hollow insulating body, a pair of contact blades, each of said blades having an aperture therethrough, a fusible element, means for removably attaching said fusible element to said contact blades, a pair of centering washers for each of said contact blades, each of said washers having a tongue adapted to pass through the aperture in said contact blade, said washers overlying each other, and means for removably securing said washers to the ends of said insulating body, substantially as described.

7. In a refillable cartridge fuse, the combination of a hollow insulating body, a contact blade at each end of said body, a fusible element, means for removably securing said fusible element to said contact blades, and removable means for alining and centering each of said contact blades, said alining and centering means having gas escape passages therein for directing the gases

generated by a blow-out in a path substantially at right angles to the main axis of the fuse, substantially as described.

8. In a cartridge fuse, the combination of
5 a hollow insulating body, a pair of contact
blades projecting into the ends of said body,
each of said blades having an aperture
therein, a fusible element, means for attaching
said fusible element to the inner ends of
10 said contact blades, a pair of slotted centering
washers fitted to each of said blades and
passing through said aperture, said washers
overlying each other and adapted to be applied
15 to said blade from opposite directions,
and removable means for securing said
washers in position at the ends of said insulating
body, substantially as described.

9. In a cartridge fuse, the combination of

a hollow insulating body, a pair of contact blades projecting into the ends of said insulating body, each of said blades having an aperture therein, a fusible element, means for attaching said fusible element to the inner ends of said contact blades, a pair of centering washers engaging opposite faces 25 of each of said contact blades, said washers overlying each other and each of said washers having a projection passing through the aperture of said contact blade, and removable means for securing said washers at the 30 ends of said insulating body, substantially as described.
